UNITED STATES PATENT OFFICE

1,985,180

METHOD AND MACHINE FOR MANUFACTURING BOXES, SUCH AS MATCH BOXES

Frédéric Mange, Paris, France, assignor to Société Indo-Chinoise Forestière et des Allumettes, Paris, France, a company of France

Application January 11, 1933, Serial No. 651,187
In France January 11, 1932

18 Claims. (Cl. 93—40)

The present invention has for its object a method of manufacturing finished and labelled boxes for the sale of matches or other products that are sold in boxes of that type. Said boxes comprise an outer part or case, and an inner part, or drawer, containing the matches and adapted to slide in the case.

The method according to my invention consists in manufacturing each of these two parts (the case and the drawer) with a single shaving, each shaving being obtained from a block of a soft or half-soft wood, previously sawed, by an ordinary sawing machine, to the height and width required for the desired size of boxes, the length of said blocks depending on the diameter of the logs.

Said shavings undergo the following operations:

(1)—The blocks are cut so as to obtain shavings of determined and uniform thickness, which is preferably the same for both the case and the drawer;

(2)—The shavings are cut so as to produce grooves therein, in order to facilitate the subsequent folding at right angles of said shavings;

(3)—In the case of the shaving being intended to form a case:

(a) The shaving is folded symmetrically at right angles, and on either side of a middle branch, so as to form a kind of U the base of which consists of one of the small sides of the case and the branches of which form the two large sides, that is to say the upper face and the under face of the case;

(b) The ends of the branches of the U are bent at right angles toward each other so that they cover each other and thus form the second small side of the case, which is opposed to the first one;

(c) The case is surrounded, on nearly the whole of its periphery, with a band of glued paper which maintains the case in its definitive shape;

(d) The label of the firm that manufactures the matches is posed on one of the large sides of the box; an advertising piece of paper is eventually fixed on the opposite side, and the friction surface, or surfaces, is, or are, fixed on the small sides.

(4)—In the case of the shaving being intended to form a drawer:

(a) The shaving is mechanically cut so as to have an accurate outline presenting a projecting part on either side;

(b) The shaving is again cut, in a direction at right angles to that of the preceding operation. These two operations limit a rectangular central surface (which will form the bottom of the drawer) surrounded by four rectangular surfaces having the same width (which will form the sides of the drawer);

(c) The shaving is folded along the tracing

resulting from the two preceding operations, so as to place the sides of the drawer at right angles to the bottom thereof;

(d) A band of glued paper is applied along the periphery of the drawer, that is to say along the four sides thereof, and said paper is then folded, on the one hand upon the outer surface of the bottom of the drawer, and on the other hand upon the upper edges of the inner faces of the sides or walls of said drawer, said band of paper thus maintaining the drawer in its definitive form.

The drawer is made of a single piece of wood, while, up to the present time it consisted of a bottom and a separate piece forming the four sides, said two pieces being assembled together by means of a sheet of paper. This mode of construction has many advantages among which I may indicate that the bottom of the drawer is perfectly flat and not warped as it used to be in many match boxes. Furthermore, there is no discontinuity between the bottom and the vertical sides.

My invention further comprises the devices for manufacturing the two parts of the box, i. e. it comprises two machines for automatically manufacturing the case and the drawer respectively, said machines being preferably individually fed by a machine for cutting the shavings.

My invention further comprises the arrangement of the devices for controlling said machines so that said machines work at the same rate and produce the same number of cases and of drawers.

A preferred embodiment of my invention will be hereinafter described with reference to the accompanying drawings, given merely by way of example, and in which:

Figs. 1, 2, and 3 are an elevational view, a side view, and a plan view respectively of the whole of the part of the machine for the manufacture of the cases of the match boxes.

Figs. 4, 5 and 6 are views corresponding to Figs. 1, 2 and 3 respectively, showing the part of the machine that manufactures the drawers;

Figs. 7, 8 and 9 are a front view, a side view, and a plan view respectively, at an enlarged scale, of the part of the machine that cuts off the wood shavings;

Fig. 10 is a detail view at a still enlarged scale showing how the wood is cut in order to obtain a shaving, and also the device for holding the blocks in position;

Figs. 11 and 12 are general views at the same scale as Figs. 7, 8 and 9, showing in elevation and in side view the part of the machine for the manufacturing of the cases;

Fig. 13 is a plan view showing how the finished cases are evacuated;

30 Figs. 41 and 42 are partial views at an enlarged scale corresponding to Figs. 26 and 27 respectively and showing in detail how the shaving is fed to the conveyer frame;

Fig. 43 is a transverse sectional view corresponding to Fig. 41;

35 Fig. 44 is a view similar to Fig. 43, some organs having been displaced;

Fig. 45 is a detail view showing in elevation a push piece;

40 Fig. 46 is a perspective view showing how the drawer is manufactured from a single shaving;

Figs. 47 to 51 are diagrammatical views illustrating the different steps of the application of the paper band;

45 Fig. 52 is a perspective view of a drawer covered with its band of paper before the upper portion thereof has been folded inside said drawer;

Fig. 53 is an elevational side view showing the control of the knives and of the members for folding and posing the band of paper on the drawers;

50 Figs. 54 and 55 show diagrammatically how the members for folding the paper operate;

Fig. 56 is a partial plan view corresponding to Fig. 53 and showing how the rollers that control the said members operate;

55 Figs. 57 and 58 are elevational views showing how the finished drawers are evacuated;

Fig. 59 is a side view corresponding to Fig. 57;

Fig. 60 is a detail view of the cam that controls the operation of the rollers for unwinding the 60 band of paper;

Fig. 61 is a plan view showing the developed profile of the cam shown in Fig. 60;

Fig. 62 is an elevational view showing the whole of the device for folding the band of paper inside 65 the drawers;

Fig. 63 is a sectional view on the line 63—63 of Fig. 62;

Fig. 64 is a cross section on the line 64—64 of Fig. 62 showing the folding of the paper band, the 70 organs for performing that operation being spaced apart;

Fig. 65 is a partial view showing said organs in their operative position;

Fig. 66 is a plan view showing how said organs 75 are disposed;

Fig. 67 is an elevational view of Fig. 66.

As shown in the drawings, and as it will be successively explained, the machine for automatically and completely manufacturing match boxes comprises several parts or elements, to wit:

5

1. An element for cutting off the shavings;

2. An element for the manufacture of the cases or outer parts of the boxes; and

3. An element for the manufacture of the drawers or inner parts of the boxes, in which the 10 matches or other objects are disposed.

One of the features of the machine according to the present invention lies in the fact that the element for cutting off the shavings can be made to cooperate with either of the two other elements, that is to say either with the part for the manufacture of the cases or with the part for the manufacture of the drawers.

Obviously the manufacture of complete boxes necessarily involves the manufacture in parallel 20 of the cases and of the drawers and that is why, in the general drawings, I have shown on the one hand in Figs. 1 to 3 the group for the manufacture of the cases, and on the other hand in Figs. 4 to 6 the group for the manufacture of the drawers.

25

Device for cutting off the shavings

Referring to Figs. 7 and 8, which are views at an enlarged scale, the cutting off of the shavings takes place as follows:

30

1 is the block that is being cut, said block being provided with a notch 2 for causing the stopping of the machine when there remains but a small portion of the block to be cut. Other blocks 1a, 1b, 1c, are disposed behind the block 1 that is being 35 cut. Said blocks are disposed one behind the other in a feed passage comprising two parts, the rear part 3, of any proper length sufficient for ensuring the feed during a certain time, and the front part 4, which is movable and is a part of the 40 machine. Said part 4 is so arranged as to have a forward and backward movement which can be adjusted according to the thickness of the shavings to be obtained; said forward movement conveys the block in such manner that it does not 45 undergo any deviation in its position.

50

During the tracing and cutting operations, block 1 is strongly held by lateral jaws 5 and 5a and by upper and lower jaws 6 and 6a respectively

55

After a shaving has been cut off, jaws 6 and 6a, which are connected together through levers 7 and 8 and connecting rod 9, are given an opening movement by lever 10, operated through cam 11.

60

After said opening of the jaws, a cam 12 connected to movable passage 4 through lever 13 produces a backward movement of the passage equal to the thickness of the shaving to be obtained. Jaws 6 and 6a, which are pivoted about axes 14, 14a, move together with movable passage 4 during the backward movement thereof.

65

Jaws 6 and 6a are then closed again by the action of cam 11.

68

While these movements are taking place, block 1 has not moved since it is still strongly held between jaws 6 and 6a.

73

After the closing of jaws 6 and 6a, lateral jaws 5 and 5a, which are connected together through levers 15 and 15a and connecting rod 16, are opened by the action of lever 5b controlled by cam 17.

78

After said opening, passage 4 comes back to its original position, the block being still tightly held by jaws 6 and 6a. Jaws 5 and 5a are then closed by the action of cam 17.

83

It will be noted that, with the arrangement ac-

75

According to my invention, the blocks are constantly strongly held in the desired position by at least two jaws. I thus avoid any possible deviation in its position and obtain a mathematical 5 regularity in the thickness of the shavings obtained and the depth at which the grooves for the folding are made and an accurate parallelism between said grooves and the upper and lower edges of the shaving. The following blocks are 10 maintained in contact with block 1 by a system of counterweights 18.

Opposite feed passage 1 there is disposed a frame 22 carrying the tracing cutters 19, which are mounted at the proper interval from one 15 another. Said cutters are given their rotary movement through a flexible shaft 20 connected to a small electric motor 21. Support 22 slides in a slideway 23 in which it is moved through the action of a lever 24 controlled by a cam 25. Support 20 25 is itself adjustable so as to vary the depth of the grooves made by the cutters 19 in the shaving. After the block has been moved forward, cutters 19 pass in front of it, in the direction of the arrow 26, and perform the tracing on said 25 block. As clearly shown by Fig. 7, said tracing takes place in a cross-wise direction with respect to the fibres of the wood and will subsequently permit the rectilinear folding to the desired shape.

30 Immediately after the translatory movement in the direction of arrow 26 of the frame supporting the tracing cutters, the shaving is cut off by means of knife 27 guided in a slide 28 and which is given its reciprocating motion by connecting rod 29 actuated by eccentric 30. Said knife thus detaches a shaving 31, as clearly shown in Fig. 10.

The shaving is then taken by a pneumatic conveyor 32, which is given, at the proper times the 40 rotary, forward and backward movements indicated by arrows 33, 34, 35 and 36, which correspond to the order of the operations. Rotary movements 33 and 36 are given by cam 37, (Figs. 8 and 9) connected to the conveyor through lever 45 38, rod 39 and lever 40.

The forward movement 34 and the backward movement 35 are produced by cam 41, connected to the conveyor through lever 42, connecting rod 43 and sector 44. In order to permit these 50 placements, conveyor 42 is mounted on slideway 45.

After its rotation corresponding to arrow 35, conveyor 32 brings shaving 31 to the second part of the machine for the manufacture of the case 55 or of the drawer.

The width l (Fig. 10) of the block that is being cut decreases, every time a shaving is detached, by the thickness of said shaving. After a certain number of cutting operations, that is when 60 the width l is only equal to about 3 or 4 millimeters, it becomes insufficient for resisting the action of the knife and giving good shavings. The unsatisfactory shavings that are then produced are then evacuated by an ejection device, which stops both conveyor 32 and the second part 65 of the machine.

To this effect, a contact piece 46 (Fig. 7) is presented, at each cycle of the machine against 70 the upper face of the wood block. Said piece 46 is given its movement by a cam 47, a connecting rod 48 and a lever 49.

When notch 8 is brought, by the successive 75 placements of the wood blocks, opposite said contact piece 46, Fig. 10, said piece is allowed to move

downwardly to a greater distance under the action of spring 50.

In the course of this displacement of greater amplitude, it closes an electric contact 51, which energizes an electro-magnet 52. The inward displacement of the core 53 (Fig. 9) of the electro-magnet causes the uncoupling of clutch plate 54, through the action of lever 55.

Plate 56, which is integral with the means for driving the conveyor and the second part of the 10 machine, is then free and kept stopped by the action of a brake 57 integral with lever 55. Fig. 9 shows the organs above stated in the position corresponding to the uncoupling of the second part of the machine, for which pneumatic conveyor 32 is also stopped.

While the conveyor and the second part of the machine are stopped, passage 4 is kept moving its reciprocating motion. At the end of each forward stroke, knife 27 cuts a shaving which 20 is immediately evacuated from the machine through any known means, for instance through the action of a pneumatic organ for the suction of saw-dust.

Knife 27 thus successively cuts the number 25 of shavings at the end of the block that cannot be utilized until the following block, 1a for instance, has had one or two shavings detached from it (so as to have a perfectly plane face for the tracing operation).

At that time, contact piece 46, which has been raised by the action of cam 47, opens electric contact 51, which causes plate 54 to be brought into clutching engagement so that the organs 35 that were precedently stopped are now again started. The shavings that are cut off are received by pneumatic conveyor 32, subsequently bringing them to the second element of the machine, for the manufacture of either the cases or the drawers.

30

40

45

Manufacture of the cases

Figs. 11 and 12 are general views at an enlarged scale of the whole of the part of the machine that is intended to manufacture the 45 cases. Said part is combined with the element for the cutting of the shaving as shown in Figs. 1 to 3.

The second part of the machine receives its motion from the first part through a plate 56, 50 which as above explained, stops the movement of said second part of the machine and also of the cams 37 and 41 that control the pneumatic conveyor 32, when the ends of the blocks are being evacuated.

While the machine is working normally, each of the shavings 31 is brought by pneumatic conveyor 32 in front of a mandrel which is a part of a series of mandrels 59a, 59b, 59c, 59d, etc., carried by an endless chain 59 meshing with 60 two toothed wheels 60 and 61, one of which 61 serves to drive the chain. Said wheel 61 is driven through a Maltese cross 62 the roller plate 63 of which is driven by the first part of the machine through shaft 64 and plate 56.

The upper portion of the mandrel carrying chain is guided by a suction passage 65 located over said chain and by a rectilinear member 66 located under it (Fig. 23). This guiding arrangement maintains that portion of the chain 70 in its rectilinear position. Likewise, the lower portion of the chain is guided between two rectilinear members 67 and 67a (Fig. 12).

Referring to Figs. 22 and 23, it will be seen 75 that each of the mandrels 59a, 59b, 59c, projects

from one side of the chain. The section of each mandrel corresponds to the internal dimensions of the case to be manufactured and the length of the mandrel is slightly longer than that of said cases.

The mandrels are hollow and are connected with suction passage 65 through a channel 68.

Passage 65 is divided into two compartments 65a and 65b.

10 Compartment 65a is connected through a pipe 71 with a valve box 72. The action of cam 73 on valve 75 brings compartment 65a into communication, at the required time, with a vacuum pump connected with the valve box through pipe 74a.

Compartment 65b is constantly connected with the vacuum pump through a pipe 74b.

It follows from that arrangement that mandrel 59b (Fig. 11) is brought into communication with a vacuum pump at the very time when it is receiving a shaving, while mandrels 59c, 59d, 59e, 59f are constantly subjected to the action of a vacuum.

23 Pneumatic conveyor 32 brings the shaving in front of the first mandrel that is taken into account for explaining the operation of the device, that is mandrel 59a, as shown in Fig. 14.

The shavings are conveyed vertically and brought in front of their respective mandrels in such manner that the two grooves previously traced thereon that limit the simple small side of the case to be manufactured register exactly with the edges that limit the front face of the mandrel. At that time, chain 59, which is not shown in the diagrammatic views of Figs. 14 to 20, is given its first forward displacement and mandrel 59a pushes shaving 31 in the direction of arrow 76. Adverting to Fig. 15, it will be seen that shaving 31 is inserted by mandrel 59a between rollers 58, 58a, said rollers fold the shaving as shown in dotted lines in 31a so as to form a kind of U the base of which consists of one of the small sides of the case to be formed and the branches of which form the two large sides thereof, that is to say the upper face and the under face.

As above explained, cutters 19 had already "traced" the shaving, which means that at each place where said shaving is to be folded, for instance at 31b and 31c, said cutters had removed a small portion of the wood so as to form a groove, the sides of said groove making between them an angle of 90 degrees in order that the folding may be made at right angles.

55 Mandrel 59a, in the course of its translatory displacement in the direction of arrow 76, brings the shaving between rollers 77 and 77a, which keep it applied against the faces of the mandrel before rollers 58—58a have ceased to act.

60 Owing to the fact that the endless chain is driven by a Maltese cross, chain 59 stops when mandrel 59a is in the position shown by Fig. 16.

During that translatory motion, paper band 79, previously coated with glue, has been applied against a portion of the upper surface 31d by roller 77.

70 As it will be hereinafter explained, the preceding mandrel, 59b, carries the shaving folded on four sides, with the exception of the second covering of the rear small side, the paper band 78 that ensures the assembling of the case having been glued to the front part of the under surface 31e, the front small side 31f, and the upper face 31d.

75 The paper is stretched between the two cases

that are being formed, as shown in Fig. 16, said cases being carried by mandrels 59b and 59a respectively.

At that time, a lower cutter 79, integral with a folding roller 80 to which it is connected by member 81, adapted to slide in a slideway 82, is given, under the action of a lever 83 (Fig. 11) controlled by a cam, a rectilinear upward movement and is thus brought under paper band 78 stretched between the cases carried by mandrels 59b, 59a (Fig. 15). Simultaneously, folding roller 80 applies the second cover 84 against the first cover 92.

Lever 85 (Fig. 11), driven by a cam, now moves in a downward direction the member, adapted to slide in a slideway 86, that carries the upper cutter 88, the first folding roller 89 and the two friction rollers 90 and 91.

The first folding roller 89 now comes into contact with the first cover 92 and applies it against the rear small side of the mandrel 59a, as shown in Fig. 17.

Cam 73 then brings, as above explained, said mandrel under the action of the vacuum, thus strongly maintaining the shaving on the mandrel.

In the course of the above stated downward movement, cutter 88, by meeting with cutter 79, has severed the paper band into two parts 78a and 78b.

30 Roller 91 applies portion 78a upon the front small side of the case of mandrel 59a, the end of the paper being left hanging.

Roller 90 applies the other portion 78b against the rear small side of the case of mandrel 59b, 35 the end of said portion of the paper band being also left hanging.

In the course of the downward movement of roller 90, folding roller 80 has also moved in a downward direction, leaving the second cover 84 40 as the paper is being applied thereon by roller 90 (Fig. 18).

Piece 81 comes back to its lower position and then piece 87 is brought back to its upper position (Fig. 19).

45 The lower roller 93, the support 94 of which is guided in a slideway 95, is provided with a hole 94a for the passage of the branch of piece 81 that supports roller 80. Said support 94 is given, through a lever 96, Fig. 11, driven by a cam, a rectilinear horizontal movement in the direction of arrow 97 (Fig. 19) so that roller 93 applies the end of the paper band against the rear part of the under surface 31e of the case of mandrel 59b. Roller 93 is then immediately brought back 55 to its original position.

It will be noted that the case carried by mandrel 59b is then finished. At that time mandrel 59a holds by suction a shaving folded along four sides, with a paper band glued thereon along the front small side 31f and a portion of the upper face 31d.

The second cover of the rear small side is not yet applied in position.

At that time, due to the fact that the chain is driven through a Maltese cross, the chain is moved forward so as to bring mandrel 59a into the position of mandrel 59b.

During that forward movement, the hanging end of the paper band 78a will be applied upon the front part of the under surface 31e by its meeting with lower friction roller 93, as shown in Fig. 20.

Simultaneously, mandrel 59a has been brought into the position formerly occupied by mandrel 75

59a, thus driving together with it, and folding a new shaving 31.

The cycle of operations above described is then automatically repeated.

5 It suffices, for starting the operation of the machine, to glue, manually, the paper band 78 onto the shaving previously brought upon mandrel 59a, Fig. 20.

Adverting now to Figs. 21 to 23, it will be seen 10 that the mandrels are hollow as above stated and that their faces are provided with holes 70 through which the suction that keeps shaving 31 firmly applied against the mandrel can be exerted. The mandrels are completed by a kind of table 70a provided with a groove 70b in which fits the suction passage 65. In order to ensure a perfect fluid tightness whenever chain 59 is stopped, passage 65 is provided with a series of projections 216 (Figs. 21 and 22) under which are placed 15 the ends 70c of two adjacent tables 70a, when the chain is stopped. The distance between the axes of two adjacent mandrels is exactly equal, for each size of case, to the length of the band of paper necessary for covering the case, as 20 shown in Fig. 20, in which the case carried by mandrel 59b is finished, as far as the application of the band of paper is concerned.

When paper band 78 has been applied on the case, as above explained, the case carried by one 30 of the mandrels is brought opposite devices for posing, on the one hand a label carrying the name of the firm that manufactures the matches, and on the other hand, eventually an advertising label.

35 The label carrying the name of the manufacturing firm is posed onto the under face of the case in the position shown in Fig. 20, that is on face 31e, and the advertising label is posed on the upper face at 31d.

40 Device for placing the labels

Adverting to Fig. 12, it will be seen that in the course of their translatory movement, the mandrels and the cases that are carried by them are brought opposite a suction member 112 mounted in a slideway 113. Said suction member can be brought by a translatory movement opposite a label magazine 111. In the course of said translatory movement, said suction member passes under a roller 107 for applying glue (see detail views 24 and 25) disposed under a vessel 108 containing glue the flow of which is adjusted by means of a scraper 110.

The translatory movement of the suction member is obtained through the action of a cam 114 (Fig. 13) acting on lever 115 and connecting rod 116.

Besides that displacement, suction member 112 is given a vertical displacement under the action 60 of a cam 117 and a lever 118, said movement taking place only at both ends of the translatory displacement. On the other hand, the label magazine can be displaced vertically through the action of a cam and a lever which are not shown 65 in the drawings for the sake of clearness.

The operation of that device takes place as follows:

When the suction member is located opposite the label magazine 111, the latter moves vertically in the direction of arrow 111a (Fig. 24) and comes in contact with suction member 112, which is at that very moment, placed into communication with the vacuum pump through pipe 119 (Fig. 12), a valve controlled at the proper time 75 being interposed in the circuit of said pump.

The suction exerted by member 112 causes a label to be applied thereon, and magazine 111 then moves upwardly in the direction of arrow 111b (Fig. 24).

Suction member 112 then moves in the direction of arrow 112a; it passes under roller 107, which is caused to rotate by the friction of roller track 112b (Fig. 25) on milled rollers 107a disposed on either side of roller 107.

As the suction member further moves in the direction of arrow 112a, it comes opposite the mandrel and is then moved vertically in the direction of arrow 112c. In the course of that movement, it applies the label, which has just been coated with glue, upon surface 31e. The label 15 being brought exactly flat wise and suitably maintained by suction member 112, is thus perfectly well posed on the case. The connection with a vacuum pump is then cut off and the inside of said suction member is connected with the atmosphere. 20

Suction member 112 then moves back in the direction of arrow 112d but by a distance greater than on its preceding upward movement so that, in the course of its return stroke, in the direction 25 of arrow 112a roller-tracks 112b are not in contact with rollers 107a and suction member 112 is kept sufficiently apart from roller 107 in order not to be soiled by it.

Roller 107 therefore rotates only in one direction, when a label is passed under it.

The arrangement of roller-tracks 112b the height of which above the plane of suction member 112 can be varied, makes it possible to complete the regulation of the flow of glue, which regulation is already obtained through the action of scraper 110. This is due to the fact that the rate of flow of the glue also depends on the clearance existing between roller 107 and suction member 112 (Fig. 25).

When member 112 is again located opposite magazine 111, it is given an upward movement in the direction of arrow 112f which brings it back into its original position where it is ready for a new series of operations.

The advertising label is posed immediately after the firm label has been posed. The device for performing that operation is shown in Fig. 14 (left hand side part thereof).

It is supposed that the case that is to receive 50 the advertising label is carried by mandrel 59d. Said mandrel is, in the course of the translatory displacement of the chain, brought opposite a glue reservoir 103 provided with a roller 102 for spreading the glue and with a scraper 109 for regulating the rate of flow of the glue.

Glue reservoir 103 is controlled by a lever 99 subjected to the action of a cam 98 which causes said reservoir to move down and roller 102 to be applied against the upper surface 31d of the case 60 of the match-box, which will be coated with glue due to the translation of the mandrel carrying chain that brings mandrel 58d into the position occupied by mandrel 58e (Fig. 14) under the label magazine 100. At this time the chain stops for a certain period (due to its intermittent driving through the Maltese cross) and cam 98 causes the downward displacement of magazine 100, and on the contrary the upward displacement of glue reservoir 103 thus releasing roller 102.

On its downward displacement, label magazine 100 distributes a label which is kept on the case by the adhesion of the glue previously spread on the upper face of said case.

The upward movement of roller 102 has been 75

provided in such manner as to avoid the formation of a roll of glue which might be produced on the small side 31^f of the case when said case arrives opposite roller 102. The outline of cam 98 is such that roller 102 is already sufficiently high before the next roller arrives in order to avoid that drawback.

After they have been posed, the upper and under labels of the case are both simultaneously tapped by brushes 101 and 106 (Fig. 14) the movement of which is produced by cam 98.

The operation of that device takes place as follows:

When the chain stops after having brought mandrel 59^e into the position previously occupied by mandrel 59^f, cam 98 causes, through lever 99, brush 101 to move downwardly, while it causes, through levers 104 and 105 brush 106 to move upwardly. Both brushes are therefore applied simultaneously onto the labels, so as to apply them perfectly on the case and to remove any excess of glue that might exist for any reason whatever.

Just before the chain is going to move again, cam 98 moves brushes 101 and 106 away from the case so as to allow a new mandrel to be brought into position.

When it is not necessary to pose an advertising label, roller 102 can be easily brought out of action. Besides it would be sufficient to remove the glue from the reservoir.

The band of paper 78 through which the cases are assembled comes from a reel 128 that is unwound in accordance with the working speed of the machine through belts 129 and 130 (Fig. 11). A portion 131 of said paper band is left slack for safety purposes. The band of paper passes under a glue pot 132 provided with a scraper 133 for evening the flow of glue in a suitable manner.

When they leave the brushing device, the cases are brought to another station for receiving the friction plate or plates that are to be placed on the small side or sides of the case. The case is then wholly finished after having undergone the following treatments:

Cutting of a shaving;
Folding of said shaving;
Application of a band of paper for assembling the folded shaving;
Application of one or two labels;
Application of the friction plates.

Removal of the finished cases

The cases thus finished may be left on their respective mandrels until said mandrels arrive to the rectilinear lower portion of the chain.

The ejecting device is shown in plan view in Fig. 13 and also sufficiently illustrated in Fig. 12.

The ejector 120 is provided with two forks which are integral with it.

The first fork comprises two branches 121, 121^a located on either side of one mandrel.

The second fork comprises two branches located on either side of the preceding mandrel.

These two series of branches are located in vertical planes the distance between which is equal to one half of the stroke of ejector 120.

Said ejector 120 is given its motion through cam 123 and lever 124. It is guided in its movement by slideway 125.

When the endless chain is not moving, the movement of the ejector causes one case to be partly removed from one mandrel through the action of branches 121 and 121^a of the first fork. The ejector is then brought back to its initial position.

A new forward movement of the chain brings said mandrel, partly freed from its case, opposite the branches 122 and 122^a of the second fork.

The following displacement of the ejector removes completely the case from the mandrel, while the other fork is partly removing the case from the new mandrel that has been brought opposite it.

The ejected case is softly dropped onto an endless band 126 moving in an intermittent manner, which is given its movement from wheel 60 through chain 127 and thus removes the case toward the outside (Fig. 11).

The removal of the cases can be performed still more softly by providing a greater number of forks adapted to cooperate with a greater number of mandrels and by reducing the ejecting stroke of piece 120 to a sufficient degree.

The preceding explanations show how are manufactured the outer parts or cases of the boxes, which act as slides for receiving the inner part or drawer of the box.

Manufacture of the drawers

The drawers are made on the special part of the machine provided for this purpose.

Figs. 4, 5 and 6 are general views of said part of the machine shown coupled with the device for cutting the shavings as above described.

In these general views, the same reference numbers serve to designate the parts above described: feed passages, knife for cutting off the shavings, jaws for maintaining the blocks of wood to be cut, series of cutters, and so on.

The set of cutters for tracing the vertical grooves in the shaving is carried by another part of the machine as will be hereinafter described, in order to avoid complication.

As above explained, the drawer consists of a single shaving, suitably cut and folded, as shown in Fig. 46, where I have shown in dotted lines the shaving 250 provided at its four corners with a notch 251, so that the drawer can be formed by raising the edges.

The wooden blocks 1, 1^a, 1^b, etc., in which the shavings are successively cut, have approximately accurate dimensions obtained when sawing said blocks, but such an approximation is not sufficient for obtaining subsequently a perfect drawer. In order to obviate that drawback, the shaving, in the course of the operations to which it is subjected for making the drawer, is punched so as to give it the mathematically accurate shape and size that are required along its whole outline.

I will now describe, with reference to Figs. 30 to 40, in what manner the shaving from the cutting device is treated. Immediately after the cutting operation shaving 250 is brought by pneumatic conveyor 32 (Fig. 6) the movements of which have been above described with reference to the manufacture of the cases, in front of push piece 135 located opposite sliding frame 134 (Figs. 5 and 6). Said frame is guided in a slideway 154 and is given a reciprocating motion through a lever 155 controlled by a cam 156 (Figs. 26 and 27).

In the course of its translatory movement, frame 134 passes in front of a series of devices provided for the working of the shaving, to wit:

Push piece 135, which inserts the shaving brought by conveyor 32 into a compartment of frame 134;

Punch 139 and bolster 140, which cut out the shaving;

Set of cutters 144, for tracing the vertical

grooves in the shaving in combination with a push piece 150; and

Push piece 159, which folds the shaving and subsequently adapts it onto a mandrel on which 5 said shaving will be covered by a band of paper by means of which it is assembled.

All these organs are actuated through the first part of the machine, the driving disk 56 thereof being, as above explained stopped when the 10 ends of the blocks are being ejected, the pneumatic conveyor 32 being also stopped during these periods. The motion is transmitted to shaft 215 through a chain 215.

When the machine is running normally, shaving 15 250, brought in front of push piece 135 is inserted by the latter into compartment 253, as it will readily be understood by referring to sectional views 43 and 44 which show (respectively before and after the insertion of shaving 250 into frame 134) the position of push piece 135. Said figures show the respective position of ejector 231, the function of which will be hereinafter described. Attention is called, in Fig. 43, to the shape of push piece 135, which is hollowed out 20 so as to allow the passage of conveyor 32. Said push piece 135 is integral with a support 136 guided in a slideway 137 and is given an intermittent reciprocating movement through a cam 138 (detail view 43 and general view 27).

When shaving 250 is inserted in the first compartment 253, as shown in Fig. 30, frame 134 is displaced toward the right hand side, in the direction of arrow 256, and comes into the position shown in Fig. 31, in which compartment 253 has been brought opposite punch 139 and its bolster 140. At this time, cam 141 produces a forward movement of punch 139, the outline of which corresponds to the desired outline of the shaving in order to obtain a box of a given size.

Punch 139 causes shaving 250 to penetrate into bolster 140, which is completed by a push piece 142 suitably guided in 142a. Said push piece 142 is made integral with punch 139 through a connecting rod 143.

When shaving 250 has been inserted into the bolster, the punch is moved slightly in a backward direction and allows frame 134 to move in the direction of arrow 257 so as to come back to its initial position. In that return stroke, frame 50 134 carried together with it the remainder 258 of the shaving 250 (shaving 250 being now cut as shown in Fig. 39). Furthermore, the shaving is provided with two grooves 259 made by the set of cutters 19 (Fig. 40).

The frame being now back to its initial position, as shown in Fig. 33, the remainder 258 of the shaving is then driven out from compartment 253 by the action of ejector 231, which comes from the position shown in Fig. 44 into the position shown in Fig. 43. The remainder 258 of the shaving is then driven out from compartment 253 and can then be evacuated in any suitable manner for instance by a vacuum cleaner for the removal of the waste.

Conveyor 32 has simultaneously brought a new shaving 260 in front of push piece 135, which is then actuated by cam 138 and causes shaving 260 to be inserted into the first compartment 253, as shown in Fig. 33.

Simultaneously, punch 139 has been moved in the direction of arrow 261 by cam 141. In the course of that backward movement, push piece 143 has inserted shaving 250 (now cut to the desired shape) into compartment 254, as shown by 75 Fig. 33.

Frame 134 is now moved in the direction of arrow 256, this displacement being intended, as above stated, to bring compartment 253 into its position opposite punch 139. As a result of this displacement, compartment 254 has brought shaving 250 opposite the set of cutters 144 and push piece 150, controlled by a cam 151, which determines its sliding in a guideway 152.

Said push piece is hollow and can be placed into communication with a vacuum pump 10 through a system of valves analogous to that described for the part of the machine that makes the cases, and which is controlled at the suitable time.

Said push piece further comprises a counter- 15 plate 153.

When frame 134 is in the position shown in Fig. 34, cams 141 and 151 cause the forward movement on the one hand of punch 139, wh ch acts on shaving 260 in the same manner as above 20 described for shaving 250, and on the other hand of push piece 150, which moves in the direction of arrow 262 and is simultaneously placed into communication with a vacuum. Shaving 250 is therefore strongly held by the head of push piece 25 150 and is appl ed by the latter against cutters 144, which trace vertical grooves 263 shown in Fig. 40. Said cutters are mounted in a support 145 guided in a slide 146 and are given an intermittent vertical reciprocating movement 30 through the intermediary of a connecting rod 147, dr ven by a lever 148, which is itself controlled by a cam 149 (Fig. 27).

When grooves 263 have been made by the downward movement of the cutters, cams 141 35 and 151 cause punch 139 and push piece 150 to move sufficiently in a backward direction for permitting the passage of the frame moving in the direction of arrow 257; and carrying together with it the remainder 258 of shaving 260, which 40 will be ejected as above expla ned by ejector 231.

A shaving 270 is then inserted into the first compartment 253 while, owing to the action of cams 141 and 151, shavings 260 and 250 are be- 45 ing engaged into compartments 254 and 255 re- spectively. Shaving 260 is driven by push piece 142 and shaving 250 is driven by counter plate 153 fixed to push p ece 150.

Therefore, all the cases of frame 134 are pro- 50 vided with shavings, compartment 253 being provided with a shaving that has just been cut, as shown in Fig. 38, compartment 254 being pro- vided with a shaving that has been punched as shown in Fig. 39 and compartment 255 be ng pro- vided with a shaving that has been both punched 55 and grooved, as shown in Fig. 40.

Frame 134 is then moved in the direction of arrow 256 and therefore brings shaving 250 op- 60 posite a folding push piece which will be here- inafter descr bed. In the course of this move- ment, shaving 260 has been brought opposite the set of cutters 144 and shaving 270 has been brought opposite punch 139. It will be readily understood that, from that time on, the operations above described, which successively bring the shavings opposite the punching device, and then the cutting device and finally the fold ng device, are automatically repeated, thus insuring the continuous working of the machine.

Folding member 159 which has just been re- 70 ferred to, and which serves to remove the shav- ing from compartment 255 at the required time, comprises four rollers 158 the axes of which are parallel two by two, being carried by flex ble arms 158a (Figs. 36 and 37) fixed to support 75 159.

guided in slideway 160 and actuated by cam 161 (Fig. 27). The end of support 159 carries a plate 162 which is elastically connected thereto at 162a. Opposite said folding member, there is brought a mandrel 164, which is one of a group of four, carried by a plate 163 and the function of which will be hereinafter described.

Once the frame has brought shaving 250 opposite mandrel 164, cam 161 causes the forward movement of push piece 159; plate 162 pushes shaving 250 and applies it against mandrel 164. As the cam further rotates, push piece 159 then moves and rollers 158 fold the sides 252 of shaving 250 as shown in Fig. 37.

15 The shaving is folded at the very place of the grooves 259, 263, which correspond exactly to the edges of mandrel 164. At this time, mandrel 164, is connected, through a suitable device, with a vacuum pump which determines a suction that 20 strongly applies shaving 250 upon said mandrel and the folding member can move backward under the action of cam 161, that movement causing the backward displacement first of rollers 158 and then of plate 162.

25 Frame 134 comprises, besides its compartments 253, 254 and 255, hollow portions 271, 272, and 273 for the passage of the various organs, punch, push pieces, etc., when said frame is being moved as explained. Furthermore, frame 134 moves between walls of a particular structure, consisting for instance of flat springs suitably distributed, not shown in the drawings, which are intended to maintain the shavings in suitable position during the displacements of the frame. Furthermore and especially for compartment 253, the inner edges of the compartments may be provided with small clips, which project very slightly therefrom, and insure a better positioning of the shaving in the compartment.

40 The details above referred to have not been shown in the drawings so as to avoid confusing them, these details being very easy to imagine.

Mandrel 164 above referred to is carried by a plate 163 which supports mandrels 164, 164a, 45 164b and 164c (Figs. 26 and 28).

The mandrels are disposed in such manner that the outer large side of each of them is in line with the outer small side of the mandrel located ahead of it. The mandrels that will occupy successively positions 164 and 164c are brought into communication with the vacuum pump through the medium of a valve controlled at the suitable time.

55 The mandrels that occupy successively the positions shown at 164a and 164b are constantly connected with the vacuum pump, as well while they are stopped as when they are rotating.

In Fig. 27, I have diagrammatically shown by means of cavity 216 and pipe 216a, the connection 60 with the vacuum pump.

In Fig. 28, the cavity of a mandrel 164 has been partly shown. The face of wheel 163 opposed to the mandrels is given the shape of a Maltese cross controlled by roller carrying disk 164 mounted on shaft 166 driven by the main shaft.

Opposite plate 163 I have provided:

1. A device comprising the following elements forming a unit: a lower cutter 167, three folding members 168, 169, 170; that device is given a reciprocating motion in the direction of arrow 70 171 (Fig. 28);

2. A device comprising the following elements forming a unit: an upper cutter 172, a folding member 173 and rollers 174, 175. Their common support is guided in slideway 176, which is given

an intermittent reciprocating motion in the direction of arrow 177. The means for operating said two devices have been shown in side view in Fig. 53.

3. A support 178 guided in a slideway 179 is given an intermittent reciprocating rectilinear movement through a lever 180 controlled by a cam 161 (Fig. 26).

Support 178 carried three rollers 182, 183 and 184, which are elastically connected thereto;

4. A roller 185 which is given a similar movement through a cam 186 and a lever 187. It is guided in slideway 188 (Fig. 27).

At the first stop of wheel 163, the shaving has been folded by rollers 158 upon mandrel 164 upon which it is kept by the effect of suction, as above explained with reference to Fig. 37.

The wheel is then given a first rotary displacement in the direction of arrow 271, thus bringing the mandrel that carries the shaving in question into position 164a when it stops, as shown in Fig. 47. At that time rollers 182 and 184 occupy their respective positions shown at 182a and 184a. They are surrounded by a band of paper 208 coated with glue, which has been applied upon the preceding drawer, as shown in position 164b.

At this time roller 185 applies the band of paper onto the outer small side of the preceding drawer, at station 164b, as shown in Fig. 48.

Rollers 182a and 184a then come into the positions 182 and 184 respectively shown in Fig. 49. They drive paper band 208 together with them and apply it against the outer large side of the drawer in question carried by mandrel 164a and keep it stretched between the two drawers.

During that displacement, the lower cutter 167 slides in the direction of arrow 272 and is brought into contact with the under side of the paper, as shown in Fig. 48.

During said upward movement, member 168 has applied the excess of paper on the inner small side against the bottom 164b of the drawer. Likewise, member 170 has folded the excess of paper on the outer large side against the bottom of drawer 164c.

The upper cutter 172 moves down and, due to its meeting with the lower cutter 167, it severs the band of paper into two parts 208a, 208b one of which 208b is applied by roller 174 against the inner large side of the preceding drawer 164b, thus completing the surrounding of the drawer (Fig. 49). The other part 208a is applied by roller 179, against the inner small side of drawer 164a, a portion of said band being left hanging.

Rollers 175 and 174 and cutter 172 move back to their initial position (Fig. 50). During said upward movement rollers 182 and 184 are kept moving, together with rollers 183. The latter applies the end of the band of paper against a part of the inner large side of drawer 165a (Fig. 60 50), while roller 182 applies it upon the outer large side of drawer 164a.

During the last mentioned operations, cutter 167 is moved in a downward direction by a distance sufficient in order that member 164 may apply the excess of paper on the inner large side of drawer 164c against its bottom (Fig. 49). It comes back to its original position (Fig. 50), leaving drawer 164c with its band of paper completely applied upon the bottom thereof.

At said station 164c, the mandrel is freed from the drawer that it carried (Fig. 50) as it will be hereinafter explained.

When the rollers occupy positions 182b, 184b, 75

185a, and cutters 167 and 172 have been brought back to their initial positions, the wheel is given its third rotary displacement, which brings it to its third stop.

5 In the course of said rotary displacement, the band of paper will be driven along by the drawer in question the apex of which moves along a circumference 163a. The backward movement (corresponding to this rotation) of rollers 182 10 and 184 passing from their positions 182b, 184b to their positions 182a, 184a will limit, through its combined action, the unwinding of the paper.

This will be understood by referring to Figs. 60 and 61, the first of which shows cam 181 and 15 lever 180 that control the displacements of the whole of rollers 182 and 184, and the second of which shows the developed outline of said cam. A careful study of said two figures will show what follows:

20 At the end of the stoppage of the mandrel carrying wheel, the roller is at A. The mandrel carrying wheel then starts rotating with the increasing speed of revolution that is imparted thereto by the Maltese cross.

25 During the rotation of the cam which brings the center of the roller into coincidence with point B, rollers 182 and 184 unwind the paper with a decreasing speed.

The total unwinding of the paper band, during 30 displacement AB is, therefore the algebraic sum of the increasing unwinding due to the rotation of the mandrel carrying wheel and of the decreasing unwinding due to rollers 182, 184 under the action of the cam. At point B, the rollers 35 are at 182b and 184b respectively. Between B and C, the return displacement of rollers 182, 184, coming back from their positions 182b, 184b to their positions 182a, 184a respectively, causes a chosen reduction of the rate of unwinding of 40 the paper due to the rotation of the mandrel carrying wheel.

When the center of the roller coincides with point C, the rollers 182, 184 are in their positions 45 182a, 184a; the mandrel carrying wheel is still rotating and it drives the paper with a decreasing speed during displacement CD. But from said point C, the action of the cam causes rollers 182, 184 to pass from their positions 182a, 184a to their positions 182b, 184b. Consequently from 50 C to D, the unwinding of the paper band is the algebraic sum of the decreasing unwinding due to the rotation of the mandrel carrying wheel under the action of its Maltese cross, and of the increasing unwinding due to rollers 182, 184, under the action of the cam.

55 At point D, the rotation of the mandrel carrying wheel is ended. During displacement DA, the unwinding of the paper takes place under the action of the rollers controlled by the cam.

60 It follows that the paper is unwound at a constant rate of unwinding (equal to that given by the cam in its portion DA while the wheel is being stopped). Portions AB, BC, CD have inclinations that are calculated in accordance with the speed due to the action of the Maltese cross in such manner that, during the period of rotation due to the Maltese cross (portion AD) the rate of unwinding of the paper band may also be 65 uniform.

70 It will readily be understood that it is possible, with such a cycle of operation, to obtain a continuous unwinding of the paper band. Said arrangement thus avoids the breaking of the paper 75 that often occurred with the prior methods.

In order to avoid that, while wheel 163 is rotating, the paper in excess (that is the portion of the paper that projects from the sides of the drawer) of the bottom of the drawer may come into contact with folding members 168, 169, said members are pivotally mounted on their supports and their angular displacement is controlled by cams, as will be hereinafter described.

5 Referring to Fig. 53, where I have shown the whole of folding members 173, 168, 169, 170, it 10 will be seen that member 173 (integral with the upper cutter, not shown) is operated through cam 217, which transmits its movements through lever 218, connecting rod 219 and lever 220.

15 Members 168, 169, and 170 (carried by the lower cutter 167, not shown) are given their movement from cam 221 and levers 222, 223, 224.

The angular displacement of members 168, 169 is effected through the action of inclined surfaces 227, 228 against which rollers 225, 226 are 20 applied by springs 229, 230.

25 While wheel 163 is rotating, members 168 and 169 occupy the positions shown by Fig. 53, which permit the passage of the excess of paper.

After the wheel has been stopped, when the 30 lower cutter moves in an upward direction, roller 225 moves along inclined surface 227, giving to the end of member 168 a displacement that brings it nearer to the bottom of the drawer, so as to make it possible to apply the paper on the bottom during the upward movement. Subsequently, on the downward displacement of the lower cutter, roller 226 acts in a similar manner, following inclined surface 228 so as to bring member 169 nearer to the drawer.

35 The removal of the drawer from station 164c, above referred to is effected by a pneumatic conveyor 193 acting in combination with a vacuum pump through valves that are controlled at the required time. The conveyor is guided in a slide-way 194 and is given its motion by a cam 195, Fig. 27.

40 As the action of the valve cuts the suction in the mandrel, the pneumatic conveyor 193 takes the drawer from station 164c. The drawer is 45 then conveyed in front of four L-shaped members 196, 196a, 196b, 196c (Figs. 62 to 67). After it has been removed from mandrel 164c, the drawer is in the state shown in Fig. 52, that is the band of paper surrounds completely the four sides 50 of the drawer and is folded against the bottom of said drawer. In other words the part shown in dotted lines is applied against the bottom of the drawer.

55 Said L-shaped members are guided in slide-ways 197, 197a, 197b, 197c. This displacement is given to them by four fingers carried by their respective under surfaces and which engage four inclined slots 198, 198a, 198b, 198c respectively provided in an annular plate 199 which is given 60 an intermittent reciprocating movement by rod 200 connected to lever 187 controlled by cam 186 (Fig. 26).

65 The movement of L-shaped members 196 in the direction of arrows 201 (Figs. 28 and 62) causes a folding of the excess of paper in a plane at right angles to the sides of the drawer (Fig. 64). Said L-shaped members are given a first displacement toward the center of piece 199 so that when conveyor 193 is caused to move in the 70 direction of arrow (Fig. 64), the faces 203 of L-shaped members 196 cause the excess of the paper to be applied against the inner faces of the sides of the drawer, as shown in Fig. 65.

75 The L-shaped members are then given a fur-

ther displacement in the direction of arrow 201, which makes it possible for conveyor 193 to move back in the direction of arrow 204, without any danger of the paper rubbing against the L-shaped members, as it often happened with the prior methods.

Circular disk 199, which carries grooves 198, turns in a support 239, and is maintained in said support by plate 240 (Fig. 64).

10 Fig. 66 shows, at an enlarged scale, the L-shaped members 196 and 196a in the position that they occupy when the paper is being applied against the inner sides of the walls of the drawer. On the contrary, in Fig. 62 said L-shaped members are in the expanded position. These figures show the overlapping of the branches of said L-shaped members in order that, when the paper is folded, it may be well applied upon the whole surface of the inside of the drawer.

20 The clearance existing between L-shaped members 196 in the position shown in Fig. 66 is intended to allow for the further movement of said members in the directions of arrows 201 which permits the removal of the drawer.

25 Fig. 67 shows the same L-shaped members in elevational view. It can be seen that the ends of said members are bevelled.

For the sake of the clearness of the drawings that show the arrangement of the L-shaped members, the section of Fig. 64 is taken on the line 64—64 of Fig. 62.

30 After the projecting portion of the band of paper has been folded against the bottom of the drawer and the inner faces of the sides thereof, the drawer is caught by a pivoting arm 205 controlled by a cam 275. Said arm brings the drawer down to a band 206 which is a part of a belt conveyor. Said band is provided with a series of stops 206a acting as partitions between which the drawers are engaged, as shown in Fig. 58.

35 Of course the parts of the machine that make the case and the drawer of the box could be used without the part that cuts the shavings from blocks of wood, the shavings being obtained by 40 unwinding or merely cut from unwound bands of wood.

45 Of course, in that case, i. e., when one does not use blocks as starting material the cutting 50 device of the cutting machine is dispensed with and the shavings or bands are disposed in the supply or feed passage leading to said machine in lieu of said blocks, and, after their being grooved in the hereonbefore described manner, 55 they are transformed on to the case manufacturing machine or to the drawer manufacturing machine.

60 While I have disclosed what I deem to be a practical and efficient embodiment of my invention, it should be well understood that I do not 65 wish to be limited thereto as there might be changes made in the arrangement, disposition and form of the parts without departing from the principle of my invention as comprehended within the scope of the appended claims.

65 What I claim is:

1. A method of manufacturing a slide box comprising an outer case and a drawer adapted to slide in said case, which comprises, taking a rectangular wood shaving, cutting it so as to form 70 grooves therein in order to facilitate its subsequent folding at right angles, folding said shaving symmetrically at right angles on either side of a median band, so as to form a kind of U the base of which consists of one of the small sides

of the case and the branches of which consist of the two large sides thereof, folding the ends of the branches of the U so that they cover each other and thus form the second small side of the case, surrounding the case along nearly the whole of its periphery with a band of paper coated with glue, so as to maintain the case in its definitive form, and finally posing a label on one of the large sides of the case, then taking a wood shaving, cutting it by punching so as to give it an accurate outline provided at each corner with a notch, forming two series of grooves at right angles to each other in said shaving, the two series of grooves limiting a central rectangular surface, which will form the bottom of the drawer, surrounded by four rectangular surfaces, which will form the sides of the drawer, folding said shaving along said grooves, and posing a band of paper around the periphery of the drawer thus formed, so as to cover with said band of paper the sides of the drawer, the outer peripheral portion of the bottom thereof, and the upper portion of the inner surfaces of said sides, so as to maintain the drawer in its definitive form.

2. A method according to claim 1 further comprising cutting the shavings that serve to the manufacture of the case and of the drawer from blocks of wood so as to obtain shavings of determined and uniform thickness.

3. A machine for manufacturing a slide box including an outer case and a drawer adapted to slide in said case, which comprises in combination, means for cutting a wood shaving so as to form grooves therein in order to facilitate its subsequent folding at right angles, forming means for supporting the shaving thus grooved, conveying means for carrying the shaving from the first mentioned means to said forming means, means for folding said shaving symmetrically at right angles on either side of a median band, so as to form a kind of U the base of which consists of one of the small sides of the case and the branches of which consist of the two large sides thereof, means for folding the ends of the branches of the U so that they cover each other and thus form the second small side of the case, means for surrounding the case along nearly the whole of its periphery with a band of paper coated with glue, so as to maintain the case in its definitive form, means for posing a label on one of the large sides of the case, means for successively bringing the forming means that support the case in position with respect to the four last mentioned means, and means for removing the case from said forming means.

4. A machine for manufacturing the case of a slide box of the type including an outer case and a drawer adapted to slide in said case, which comprises in combination, cutting means for making shavings out of a block of wood, means, operatively connected with said cutting means, for intermittently feeding a block of wood toward said cutting means, means, operatively connected with said cutting means for making four parallel grooves in said block prior to the cutting off of the shaving, forming means for supporting the shaving thus grooved, conveying means for carrying the shaving from said block to said forming means, means for folding said shaving symmetrically at right angles along two of said grooves on either side of a median band, so as to form a kind of U the base of which consists of one of the small sides of the case and the branches of which consist of the two large sides thereof, means for folding the ends of the

branches of the U along the two other grooves so that said ends cover each other and thus form the second small side of the case, means for surrounding the case along nearly the whole 5 of its periphery with a band of paper coated with glue so as to maintain the case in its definitive form, means for posing a label on one of the large sides of the case, means for successively bringing the forming means that support the case in position with respect to the four 10 last mentioned means, and means for removing the case from said forming means.

5. A machine for manufacturing the drawer of a slide box of the type including an outer case and a drawer adapted to slide in said case, which comprises in combination, punching means for cutting a wood shaving to an accurate outline provided at each corner with a notch, means for forming two series of grooves at right angles 15 to each other in said shaving, the two series of grooves being so traced as to limit a central rectangular surface, which is intended to form the bottom of the drawer, surrounded by four rectangular surfaces, which are intended to form 20 the sides of the drawer, forming means for supporting the shaving thus grooved, means for conveying said shaving from said punching means to said grooving means and then to said forming means, means for folding said shaving on said forming means along said grooves, means for posing a band of paper coated with 25 glue around the whole periphery of the drawer carried by said forming means, so as to cover with said band of paper the sides of the drawer, the outer peripheral portion of the bottom thereof, and the upper portion of the inner surfaces of the sides thereof, in order to maintain the drawer in its definitive form, and means for removing the drawer from said forming 30 means.

6. A machine for manufacturing the drawer of a slide box of the type including an outer case and a drawer adapted to slide in said outer case, which comprises in combination, cutting means for making shavings out of a block wood, means, operatively connected with said cutting means, for intermittently feeding a block of wood toward said cutting means, means, operatively connected with said cutting means for making two 35 parallel grooves in said block prior to the cutting off of the shaving, punching means for cutting a wood shaving to an accurate outline provided at each corner with a notch, means for making two other parallel grooves in said shaving, at right angles to the two first mentioned ones, the two series of grooves thus traced being so disposed as to limit a central rectangular surface which is to form the bottom of the drawer, surrounded by four rectangular surfaces 40 which are to form the sides of the drawer, forming means for supporting the shaving thus formed, means for conveying said shaving from said punching means to said grooving means and then to said forming means, means for folding said shaving on said forming means along said grooves, means for posing a band of paper coated with glue around the whole periphery of the drawer carried by said forming means so as to cover with said band of paper the outer peripheral portion of the bottom thereof and the upper portion of the inner surfaces of the sides thereof, in order to maintain the drawer in its definitive form, and means for removing the drawer from said forming 45 means.

7. A machine for manufacturing the case of

a slide box of the type including an outer case and a drawer adapted to slide in said case, which comprises in combination, means for making four parallel grooves in a shaving, a mandrel for supporting the shaving thus grooved, means for bringing the grooved shaving onto said mandrel, pneumatic means for applying said shaving to said mandrel, means for folding said shaving against said mandrel symmetrically at right angles along two of said grooves on either side 5 of a median band, so as to form a kind of U the base of which consists of one of the two small sides of the case and the branches of which consist of the two large sides thereof, means for folding the ends of the branches of 10 the U against the mandrel along the two other grooves, so that said ends overlap and thus form the second small side of the case, means for surrounding the case along nearly the whole 15 of its periphery with a band of paper coated with glue so as to maintain the case in its definitive form, means for posing a label on one of the large sides of the case, means for intermittently and successively bringing the mandrel in working position with respect to the four 20 last mentioned means, and means for removing the finished case from its mandrel.

8. A machine according to claim 7 further comprising a knife for cutting shavings out of a block of wood, means, operatively connected with said 25 cutting means, for intermittently feeding a block of wood toward said cutting means, the means for making four parallel grooves in a shaving consisting of four rotary cutters operatively connected with said knife, and the means for bringing the grooved shaving toward the mandrel consisting of a pneumatic conveyer for carrying the shaving from the block out of which it has just been cut to said mandrel.

9. A machine for manufacturing the drawer 30 of a slide box of the type including an outer case and a drawer adapted to slide in said case, which comprises in combination, means for making two parallel grooves in a wood shaving, punching means for cutting a wood shaving thus provided 35 with grooves to an accurate outline provided at each corner with a notch, means for forming two parallel grooves at right angles to the first mentioned ones in said shaving, a mandrel for supporting the shaving thus grooved, a sliding frame 40 for conveying said shaving from the first mentioned means to said punching means then to said grooving means and finally to said mandrel, four rollers for folding said shaving against said mandrel along said grooves, means for posing a band 45 of paper coated with glue along the four sides of the drawer carried by said mandrel so as to cover with said band of paper the sides of said drawer, means for applying one edge of said band against the outer peripheral portion of the bottom of the drawer, means for applying the other edge of said band of paper against the upper portion of the inner surfaces of the sides thereof, in order to 50 maintain the drawer in its definitive form, and means for removing the drawer from said mandrel.

10. A machine according to claim 9 further comprising a knife for cutting shavings out of a block of wood, means, operatively connected with 55 said knife, for intermittently feeding a block of wood toward said knife, the means for making two parallel grooves in a wood shaving consisting of two rotary cutters operatively connected with said knife, the machine also comprising a pneu- 60

matic conveyer for bringing the shaving from the block of wood out of which it has just been cut to said sliding frame.

11. A machine for manufacturing the case of a slide box of the type including an outer case and a drawer adapted to slide in said case, which comprises in combination, a knife for cutting shavings out of a block of wood, means, operatively connected with said knife, for intermittently feeding a block of wood toward said knife, four rotary cutters operatively connected with said knife for making four parallel grooves in said block, a plurality of mandrels for supporting said shavings respectively, an endless chain supporting said mandrels, driving means for intermittently moving said chain, a pneumatic conveyer for carrying said shavings, successively, from said block to said mandrels respectively, pneumatic means for applying each shaving against one mandrel respectively, folding rollers, disposed along the path of said chain, for applying said shaving against said mandrel symmetrically at right angles along two of said grooves on either side of a median band, so as to form a kind of U the base of which consists of one of the two small sides of the case and the branches of which consist of the two large sides thereof, pressing rollers disposed along the path of said chain, means for operating said pressing rollers, operatively connected with the means for driving said chain, for folding the ends of the branches of the U against the mandrel along the two other grooves, so that said ends overlap and form the second small side of the case, rollers for applying against the case along the periphery thereof a band of paper coated with glue, the last mentioned rollers being disposed along the path of travel of the chain, cutters for severing said band of paper, means, operatively connected with the means for driving said chain, for operating said cutters, means disposed along the path of the chain, for posing a label on one of the large sides of the case, and means for removing the finished case from its mandrel.

12. A machine according to claim 11, further comprising means for stopping the pneumatic conveyer, the chain, and the organs that cooperate therewith when a block has been cut to a given thickness, and as long as the following block has not been started.

13. A machine according to claim 11 further comprising means for posing another label onto the other large side of the case.

14. A machine according to claim 11 in which the means for removing the finished case from its mandrel include at least one organ for starting the removal of the case from the mandrel that supports it.

15. A machine for manufacturing the drawer of a slide box including an outer case and a drawer adapted to slide in said case, which comprises in combination, a knife for cutting shavings out of a block of wood, means, operatively connected with said knife, for intermittently feeding a block of wood toward said knife, two rotary cutters operatively connected with said knife for making two parallel grooves in said block, punching means for cutting a wood shaving thus provided with grooves to an accurate

outline provided at each corner with a notch, rotary cutters for making two parallel grooves at right angles to the first mentioned ones in said shaving, a plurality of mandrels for supporting said shavings respectively, a sliding frame provided with three compartments for the shavings respectively, means for inserting a shaving into one of said holes, a pneumatic conveyer for bringing the shavings successively from said block to said last mentioned means, means for reciprocating said frame so as to bring the last mentioned compartment alternately opposite said means for inserting a shaving in said compartment and said punching means, to bring the adjacent compartment alternately opposite said punching means and the second mentioned rotary cutters, and to bring the third compartment alternately opposite the last mentioned cutters and one of said mandrels, means operatively connected with said punching means for alternatively removing a shaving from the first compartment and inserting it into the second compartment, means operatively connected with the second mentioned cutters for alternatively removing a shaving from the second compartment and inserting it into the third compartment, means, operatively connected with the means for driving said sliding frame, for pushing said shaving from the third compartment to one of said mandrels, four rollers for folding said shaving against said mandrel along said grooves, a plurality of rollers for posing a band of paper coated with glue along the four sides of the drawer thus formed, sliding means, operatively connected with said rollers for applying one edge of said band along the outer peripheral portion of the bottom of the drawer, means for supporting said mandrels, driving means for displacing said supporting means in an intermittent manner so that the mandrels are successively brought into working positions with respect to the rollers and the sliding means above mentioned, means for folding the other edge of said band of paper against the upper portions of the inner surfaces of the sides thereof, in order to maintain the drawer in its definitive form, and means for removing the finished drawer from its mandrel.

16. A machine according to claim 15, further comprising means for stopping the pneumatic conveyer, the sliding frame, the organs co-operating with said frame, and the driving means for moving the mandrels, when a block has been reduced to a given thickness, and as long as some shavings have not been cut from the following block.

17. A machine according to claim 15 in which the means for folding one edge of the band of paper against the upper portions of the inner surfaces of the sides of the drawer comprise four L-shaped members, means for moving said members radially, means for moving said drawer in a direction at right angles to the radial displacement of said L-shaped members, and means for further moving said members radially in an inward direction.

18. A machine according to claim 15 further comprising an endless belt for receiving the finished drawers, and an arm for dropping the drawers on said belt.
